Primary Examiner — Rosemary K Tarcza*Assistant Examiner* — Yolando Robinson(74) *Attorney, Agent, or Firm* — Maybeck & Hoffman, P.A.; Gregory L. Mayback(57) **CLAIM**

The ornamental design for a dermaplaner, as shown and described.

DESCRIPTION

FIG. 1 is a perspective view of a dermaplaner showing my new design;

FIG. 2 is an elevational view of a rear side thereof;

FIG. 3 is an elevational view of a front side thereof from a side opposite the view of FIG. 2;

FIG. 4 is a top plan view thereof;

FIG. 5 is a bottom plan view thereof;

FIG. 6 is an elevational view of a left side thereof; and,

FIG. 7 is an elevational view of a right side thereof.

1 Claim, 3 Drawing Sheets(56)
